Primary Examiner — Susan Bennett Hattan*Assistant Examiner* — Janice Hallmark(74) Attorney, Agent, or Firm — McAndrews Held & Malloy, Ltd.CLAIM

The ornamental design for a microphone for gaming headset, as shown and described.

DESCRIPTION

FIG. 1 is a front perspective view of a microphone for gaming headset showing my new design;

FIG. 2 is a front view thereof;

FIG. 3 is a rear view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a rear perspective view thereof.

The broken lines in the drawings depict environmental subject matter only and form no part of the claimed design.

The wavy black line at the end of the cable represents an unclaimed boundary line and forms no part of the claimed design.

1 Claim, 8 Drawing Sheets(56)
